UNITED STATES PATENT OFFICE.

ALEXANDER T. BROWN, OF SYRACUSE, NEW YORK.

TYPE-WRITING MACHINE.

984,744.

Specification of Letters Patent. Patented Feb. 21, 1911.

Application filed July 25, 1906. Serial No. 327,706.

To all whom it may concern:

Be it known that I, ALEXANDER T. BROWN, a citizen of the United States, and resident of Syracuse, in the county of Onondaga and State of New York, have invented certain new and useful Improvements in Type-Writing Machines, of which the following is a specification.

My invention relates to typewriting machines and more particularly to the type actions of such machines, although the invention is also directed to other features of the machine.

The main objects of my invention are to provide a type action that has a light touch; that affords a uniform leverage, a uniform extent of dip of the keys and a uniform touch throughout the system; that avoids side strain on the actions at the sides of the machine; that affords but slight resistance to the key depression at the initial portion of the key stroke and effects a gradual acceleration of the type bar in its movement to the printing position and that provides a construction in which various portions of the type actions may be assembled outside of the machine and introduced in an assembled state into the machine.

To the above and other ends which will hereinafter appear, my invention consists of the features of construction, arrangements of parts and combinations of devices to be set forth in the following specification and to be particularly pointed out in the accompanying claims.

In the drawings, wherein like reference characters indicate corresponding parts in the various views, Figure 1 is a vertical, central, front to rear sectional view of one form of typewriting machine showing my invention applied thereto, parts of the machine being omitted. Fig. 2 is an enlarged detail fragmentary perspective view of a portion of one of the type actions. Fig. 3 is a diagrammatic side elevation of one of the type actions and a portion of the escapement mechanism. Fig. 4 is a detail front elevation of one of the sub-levers at the right-hand side of the machine. Fig. 5 is a rear elevation of the machine with parts broken away and parts omitted. Fig. 6 is a vertical front to rear sectional view taken centrally through the machine and showing the case shifting mechanism and part of one of the type actions.

The frame of the machine comprises side

plates 1, a rear cross plate 2, a front cross bar 3, corner posts 4 and a top plate 5. Inwardly extending lugs 6 on the side plates 1 constitute supports for a supporting plate 60 7 which is detachably secured to said lugs by screws 8. The supporting plate 7 is apertured at 9 (Fig. 6) at different points throughout the width and length thereof for the reception of hanger stems 10 threaded 65 at their upper ends for coöperation with nuts 11. Depending from the stems 10 are bifurcated hanger portions 12 in which key levers 13 are received and pivoted thereto at 14, 14^a, 14^b, 14^c. The key levers 13 are provided 70 with finger keys 15, 15^a, 15^b, 15^c arranged in four banks fore and aft of the machine. The key levers are levers of the first order and have rearwardly extending, substantially horizontally disposed arms 13^a which 75 terminate at their rear ends in a single transverse plane and forwardly extending arms 13^b which carry the keys. From an inspection of Fig. 1 it will be seen that the key levers throughout the system are of four 80 different lengths and are pivoted to their hangers at different points fore and aft of the machine in four transverse planes, the shortest key levers having the finger keys 15 being pivoted at 14, the key levers having the 85 finger keys 15^a being pivoted at 14^a, the key levers having the finger keys 15^b being pivoted at 14^b and the key levers having the keys 15^c being pivoted at 14^c. By this construction the lever arms 13^a and 13^b of each 90 key lever bears a uniform ratio to each other, notwithstanding the fact that the keys are arranged in four banks and that the rear ends of the key levers terminate in a single transverse plane. The purpose of this construction is to assist in providing a uniform 95 extent of dip of the various keys and a uniform leverage throughout the system and also to effect a uniform extent of movement of the universal bar by the different key levers, all as will hereinafter more clearly appear. Each key lever has a depending arm 16 which has a hook-like member 17 at the lower end thereof with which one end of a contractile spring 18 engages, the other end 100 of said spring being connected to a rod 19 which extends transversely beneath the various key levers and is secured at its ends to the side plates 1 of the machine. The rearwardly extending horizontally disposed 105 arm 13^a of each key lever is pivoted at 20 to a link designated as a whole by the reference

numeral 21, the opposite end of said link being pivoted at 22 to the lower end of an upright sub-lever 23 pivoted at 24 to a hanger 25, the sub-lever extending substantially at right angles to the link. The upper end of each sub-lever is pivotally connected at 26 to a pull link 27 that extends forwardly and is connected at 28 to a type bar 29 having a rearwardly extending arm 30 that co-operates with a type bar guide 31 formed as a part of a hanger 32 to which the associated type bar is pivoted at 33. The various type bar hangers are secured to the rear face of a type bar segment 34 by headed screws 35.

The type bar construction is similar to that disclosed in the patent granted to me on the 19th day of September, 1905 which bears No. 799,627. The forward ends of the type bars normally rest on a pad 36 supported by a segmental strip 37 connected to arms 38 which project forwardly from the type bar segment. The type bars are segmentally arranged on the type bar segment 34 and are adapted to strike upwardly and rearwardly against the front face of the platen diagrammatically shown at 39. Pivotally connected to the type bar segment at each side thereof and near the upper portion of the segment is at 40 a forwardly projecting link 41 pivoted at its rear end 42 to a lug 43 which projects inwardly from each of the rear corner posts 4 of the frame. The links 41 constitute parallel links by which the upper portion of the segment is guided in its case shifting movement. The lower portion of the segment has outwardly projecting arms 44 (see Fig. 5) to which are pivotally connected the forward ends of arms 45 that project forwardly from a tubular member 46 which is in the nature of a rock-shaft and is provided with bearings 47 in the ends thereof for co-operation with anti-friction balls 48. Coned ends 49 of bearing screws 50 co-operate with the anti-friction balls to support the member 46 and the parts connected thereto on the frame of the machine. The bearing screws 50 are received in threaded openings in brackets 51 which project inwardly from the base of the machine; the screws being held against accidental displacement by lock nuts 52. A rearwardly extending crank arm 53 projects from the member 46 and its rear end is connected to one end of a coiled contractile spring 54 which passes at its lower end through an opening in a lug 55 that projects inwardly from a side plate 1 of the machine. The lower end of the spring is suitably connected to a thumb nut 56 by which an adjustment of the tension of the spring 54 may be effected. The spring 54 is regulated partially to counterbalance the weight of the type bar segment. The arms 45 of the tubular member 46 and the rearwardly extending arm 53

constitute a rigid frame by which the type bar segment and the parts connected thereto may receive the case shifting movements. The arms 45 extend parallel with the links 41 and constitute parallel links on which the segment can be shifted. One of the arms 45 is pivotally connected at 57 to a depending link 58 which is pivoted at its lower end 59 to the rear end of a shift key lever 60 pivoted at 61 to a stud 61^a that projects inwardly from a side plate 1 of the frame. The forward end of the key lever 60 is provided with a key 62 so that a depression of the finger key 62 will elevate the rear end of the lever, thereby causing the type bar segment to be elevated to write upper case characters. If desired each of the arms 45 may be connected with a shift key 62, said keys being situated at opposite sides of the machine and either of them being operative to change the case position of the segment. A bracket 63 is secured by screws 64 to the supporting plate 7 at about the center of the machine. A rearwardly extending arm 65 has a threaded opening therein for the reception of a screw 66 that extends through said arm and at its lower end forms a stop or abutment. A lock nut 67 is threaded on the screw to prevent accidental displacement of the stop. Below the arm 65 is another arm 68 which projects rearwardly from the bracket and has a threaded opening through which a screw stop 69 extends, the screw co-operating with a lock nut 70 which holds it in its adjusted position. Extending forwardly from the segment is a member 71 which extends into an opening between the two bracket arms 65 and 68 and co-operates with the screw stops 66 and 69 to limit the shifting movements of the segment, the segment being normally supported by the stop 69. It will be understood that the spring 54 acts as a counterbalancing spring to counteract the weight of the type bar segment and the parts carried thereby so that but little pressure is required on the shift key 62 to shift the segment to the upper case position. During the shifting movements of the segment the links 27 turn around the points 26 where they are pivotally connected in Fig. 6 and other portions of the type actions are not affected.

The rear ends of the key levers 13 normally rest on a pad 72 supported by a horizontally disposed strip 73 that extends beneath the entire series of key levers and is secured at its ends by screws 74 to inwardly projecting lugs 74^a on the side plates of the frame. The links 21 which connect the key levers with the sub-levers are preferably formed as indicated in Fig. 2 of two parallel side plates 75 and 76, pivotally united intermediate their ends as at 77 so that one of the members is adapted to turn relatively

to the other as shown in dotted lines in Fig. 2. One of the side plates 75 is a rigid member which carries laterally projecting pivot pins 78, 79 at the ends thereof, whereas the other plate 76 is slightly resilient and is preferably provided with openings 80 that are adapted to register with the pivot pins 78 and 79 when the plate 76 is turned to the full line position shown in Fig. 2 and to receive the pivot pins in said openings to prevent an accidental disengagement of the links from the sub-levers and key levers to which they are connected but to afford means for readily disconnecting the link from said members when desired.

Extending above the key levers at the rear ends thereof is a universal bar 81 with which the key levers coöperate. The contact face of the universal bar is normally in contact with all of said key levers and makes contact therewith in the same transverse plane so that it bears the same relation to all of the key levers, and a uniform extent of movement is transmitted to the universal bar by all of the key levers. Depending links 82 are secured to the universal bar and are pivotally connected at their lower ends 83 to rearwardly extending crank arms 84 of a rock shaft 85 that turns on bearing screws 85^a threaded through openings in the side plates of the frame. In order to guide the universal bar in its up and down motion, the links 82 pass loosely through suitable openings in brackets 82^a (Fig. 5) which project inward from the side plates 1. A rearwardly projecting crank arm 86 is also connected to said rock shaft and is pivotally connected at its rear end to an upwardly extending link 87 connected at 88 to a horizontally disposed lever 89 situated directly beneath the top plate 5 of the machine and pivoted at 90 to a depending lug 91 formed on the top plate. This horizontally disposed lever extends fore and aft of the machine and is provided with a depending arm 92 to which one end of a contractile spring 93 is connected, the other end of said spring being connected to a screw 94 which passes freely through an opening in a bracket 95 secured to the top plate at 96. A thumb nut 97 coöperates with the screw to effect an adjustment of the tension of the spring 93. The forward end of the lever 89 is connected directly to a ribbon vibrator 98, whereas the rear end of the lever has feed dogs 99 formed integral therewith, and coöoperating with the escapement wheel 100. The escapement wheel is secured by a screw 101 to a vertically disposed shaft 102 received in an upright bearing 103 formed on the top plate of the machine and extending above it as shown in Fig. 3. A collar 104 is secured to the shaft by a pin 105 so that the collar and the hub of the escapement wheel bear against opposite ends of the bearing 103 and prevent

a longitudinal movement of the shaft 102 in its bearing.

A feed pinion 106 has a hub or extension 107 which bears on the collar 104 to properly support the pinion in place. The pinion is loosely mounted on the cylindrical portion of the shaft 102 and has a clutch member 108 formed on the upper end thereof. A co-operating clutch member 109 is located above the clutch member 108 and is in the nature of a sleeve with a rectangular opening which coöperates with a rectangular portion 110 on the shaft 102 to cause the clutch member 109 to rotate with the shaft but to afford a movement of the clutch member axially thereof. A peripheral flange 111 is formed on the clutch member 109 for coöperation with a forwardly projecting flange 112 on a bar or bail 113 that extends throughout the length of the carriage and is provided at its ends with forwardly projecting arms 114 pivoted at 115 to end plates 116 of the carriage. One or both of the arms 114 may be extended forwardly beyond their pivots to form arms 117 that carry release keys 118 at the forward ends thereof. Each of the arms 117 is preferably slotted at 119 for coöperation with a pin 120 which projects outwardly from an end plate 116 of the carriage and into the slot 119 of the associated lever to limit the movement of the release levers 117 and the parts controlled thereby. The carriage which supports the platen 39 comprises the end plates 116 heretofore referred to and members 121, 122 provided with oppositely disposed grooved tracks 123 for coöperation with anti-friction balls 124 which are likewise received in oppositely disposed grooved tracks 125 in an inclined plate 126 secured by screws 127 to uprights or lugs 128 on the top plate of the machine. A paper table 129 is secured to the members 121 and 122. The depending flange-like portion 130 on the member 122 has fixed on its rear face a feed rack 131 which meshes with the feed pinion 106. The usual spring drum (not shown) is connected to the carriage to effect a forward step-by-step feed thereof, when the finger keys are depressed, it being understood that each actuation of a finger key will effect an elevation of the forward end of the lever 89 to operate the escapement and to elevate the ribbon vibrator 98 to interpose the ribbon in the path of the approaching type bar.

A finger key or space bar 132 is connected at its ends to two levers 133 situated on opposite sides of the machine, said levers being somewhat similar to the key levers 13. One of the levers 133 has at its rear end a downwardly extending portion 133^a and is provided at the lower end of the downwardly extending portion with an outwardly bent hook-like member 134 which extends beneath one of the crank arms 84. Each of the key levers 133 is mounted in one of the

hangers 12 carried by the supporting plate 7. A depression of the key 132 therefore is effective to elevate the arm 84 to which it is operatively connected, thus rocking the shaft 85 and causing the forward end of the lever 89 to be elevated to effect a downward movement of the feed dogs. When pressure on the finger key 132 is released the parts will be restored to their normal position, thus affording a letter space movement of the carriage. During the operation of the machine in the usual manner the feed dogs will be vibrated to afford a release of the escapement wheel and the pressure exerted on the carriage by the carriage spring will cause the pinion 106 to be rotated and the two clutch members 108, 109 being in engagement at this time a letter space rotation of the escapement wheel is effected. Should the operator desire to release the carriage from the escapement mechanism it is merely necessary to depress either of the release keys 118 which will effect an upward movement of the clutch member 109 axially of the shaft 102 by the direct engagement of the bail under the circumferential flange 111. The clutch members being thus released the carriage may be moved in either direction and the feed pinion will turn freely on its shaft.

The carriage construction hereinbefore described is somewhat similar to that disclosed and claimed in my applications, Serial Nos. 305,053 and 214,625, dated respectively March 9th, 1906 and June 29th, 1904.

From an inspection of Figs. 1 and 5 it will be seen that the vertically disposed parallel hangers 25 are all alike in construction and are arranged in an arc or at gradually higher elevations from the center to the sides of the system. Each of the hangers in question comprises a bifurcated portion in which the sub-lever is pivoted and each hanger is secured to the front face of a plate 135 by a screw 136. It will be observed that each headed screw passes from the rear through the plate 135 and is received at its threaded end in a threaded opening in the base or attaching portion of the hanger and that this threaded opening in the hanger is off-set vertically with reference to the pivot 24, or is off-set to one side of the center of the hanger, considering the center as passing at right angles from the base of the hanger forwardly through the pivot 24, thus bringing the screw hole on one side of or eccentric to the center line of the hanger. This screw hole is thus formed longitudinally of the hanger, and the fastening screw engages the hanger in the direction of its length so that one end, the base end only, of the hanger is caused to bear against the support provided for the hanger. This support or base plate 135 is provided with two concentric rows of screw holes for the ad-

mission of the screws 136, and the holes of one row are arranged to alternate with those of the other row, as seen more clearly in Fig. 5. The threaded holes in the hangers are likewise arranged to form two concentric rows and to alternate to correspond with the alternation of the holes in the support or base plate, thus providing for a close arrangement of hangers in a single row with two rows of staggered or alternating fastening screws. The construction of each hanger is such that it may be reversed and either side thereof be placed uppermost, which enables the securing screws to be arranged in staggered relation as shown in Fig. 5 while the pivots 24 are arranged in a smooth curve. The hangers are all alike, and the staggering of the screws shown in Fig. 5 is produced by setting every other hanger with its threaded opening above the pivots 24, the alternate hangers being reversed and set with their threaded openings below the pivots. As shown in the present case, all of the hangers 25 are set so that the slots in which the sub-levers play are substantially vertical. The plate 135 to which the hangers are secured is held in position by screws 137 which extend through the rear cross plate 2 and the threaded ends thereof are received in openings in the plate 135. By this arrangement, and by reason of the detachable feature of the supporting plate 7, the various key levers, their connecting links 21, and sub-levers 23 may be assembled and connected outside of the machine and introduced as a unit into the machine, the parts being readily connected and supported in place by the screws 8 and 137. It will also be seen that the construction is such that parts of each type action, or any type action as a whole, may be removed from the machine without disturbing the other type actions, or the entire system of key levers or the entire system of sub-levers may be readily removed as a unit without dismounting any of the other parts of the machine; the disconnectible links 21 facilitating the removal of either the system of sub-levers or the system of key levers when desired.

From an inspection of Fig. 5 it will be observed that the sub-levers 23 have their upper ends arranged in an arc which is substantially co-extensive with the arc in which the type bars are mounted and that in the actuation of each type action a direct fore and aft pull is effected on the link 27 to move the type bar to printing position. The lower ends of the sub-levers are arranged in a single horizontal plane so as to properly connect with the links 21 which constitute toggle links as will hereinafter appear. It will also be seen from an inspection of Fig. 5 that both sets of arms of the sub-levers are progressively longer from the center to the sides of the system

and that the sub-levers at the sides of the machine are situated in inclined planes extending inwardly and upwardly from the links 21 to the draw links 27 to which they 5 are connected. One of these sub-levers at the side of the machine is shown in detail in Fig. 4 from which it will be seen that the points of connection of the sub-lever with its link 21 and draw link 27 is in the 10 same inclined plane as the pivotal point of said lever. In other words, the pivotal connections 22, 24 and 26 are in the same inclined plane so that lateral strain is avoided. It will also be understood that 15 the converging sub-levers at the sides of the system compensate for the difference in width between the system of type bars and the system of links 21, the latter system being co-extensive in width with the system of key levers. By arranging the sub-levers in the manner described with the pivots thereof arranged at progressively higher elevations as the sides of the system are approached and by gradually increasing 20 the length of both sets of lever arms of the sub-levers as shown I am enabled not only to arrange the upper end of the sub-levers in an arc which is substantially co-extensive with the arc in which the type bars 25 are situated and to afford a direct fore and aft pull on the type bars, as hereinbefore described, but I am also enabled to provide a uniform leverage of the sub-levers throughout the system. With an equalization of 30 the leverage of the key lever system and the sub-lever system a uniform leverage through the entire system of type actions is afforded as well as a uniform touch on the various keys and a uniform extent of dip of the 35 40 keys.

From an inspection of Figs. 1 and 3 it will be seen that the rear arm 13 of each key lever and the link 21 which is pivoted thereto are both horizontally disposed in 45 the normal position thereof and are arranged end to end in alignment to form a toggle which is normally in the dead center position so as to form what may be termed a reverse toggle that effects a gradual acceleration of the type bar in its movement to the printing position, the toggle being broken by the depression of its key from the full to the dotted line position shown in Fig. 3. The effect of breaking 50 the toggle in the manner described is to pull the lower end of the associated sub-lever forward, thereby effecting a backward pull on the associated link 27 to move the type bar from the full to the dotted line position shown in Fig. 3. This same depression of a finger key is effective to elevate the universal bar as heretofore described, thereby rocking the shaft 85 to effect an upward movement of the forward end of the lever 55 60 65 89 which is effective to elevate the vibrator

and interpose the ribbon in the path of the approaching type bar. The same movement lowers the rear end of the lever, thereby actuating the feed dogs and affording a letter space movement of the carriage. 70

The carriage and ribbon vibrating mechanism shown and described is not claimed herein but constitutes the subject-matter of a separate divisional patent, dated July 26, 1906, No. 965,501. 75

Various changes may be made without departing from my invention.

What I claim as new and desire to secure by Letters Patent is:—

1. In a typewriting machine, the combination of a series of substantially horizontally disposed key levers, a series of substantially horizontally disposed links pivoted to said key levers at the rear ends thereof and arranged to extend longitudinally of 80 said key levers and toward the back of the machine, a series of sub-levers pivoted to said links, and a series of type bars actuated by said sub-levers. 85

2. In a typewriting machine, the combination of a series of substantially horizontally disposed key levers of the first order, a series of substantially horizontally disposed links pivoted to said key levers and extending longitudinally thereof, a series of 90 sub-levers of the first order pivoted to said links, and a series of type bars actuated by 95 said sub-levers.

3. In a front-strike typewriting machine, the combination of a series of key levers 100 having rearwardly extending substantially horizontally disposed arms, a series of substantially horizontally disposed links pivoted to said arms, a series of upright sub-levers pivoted to said links, and a series of upwardly and rearwardly striking type bars 105 actuated by said sub-levers.

4. In a typewriting machine, the combination of a series of key levers of the first order, said key levers having rearwardly 110 extending horizontally disposed arms, substantially horizontally disposed links pivoted to said arms, sub-levers that extend substantially at right angles to said links, and type bars actuated by said sub-levers. 115

5. In a typewriting machine, the combination of a series of key levers having rearwardly extending substantially horizontally disposed arms, each of said arms forming one element of a toggle; a substantially horizontally disposed link pivoted to each of said rearwardly extending arms of said key levers and forming the other element of the toggle; a series of upright sub-levers of the first order, one pivoted to each of said links; and 120 a series of type bars connected with the upper ends of said sub-levers. 125

6. In a front-strike typewriting machine, the combination of a series of key levers having substantially horizontally disposed 130

arms that extend rearwardly beyond the pivots thereof, each of said arms forming one element of a toggle; a link pivoted to each of said rearwardly extending arms and extending longitudinally in substantial alinement therewith in the normal positions of the parts and forming the other element of the toggle; a series of upright sub-levers of the first order, one pivoted at its lower end to each of said links; and a series of upwardly and rearwardly striking type bars connected with the upper ends of said sub-levers.

7. In a front-strike typewriting machine, the combination of a key lever of the first order having a forwardly extending horizontally disposed arm carrying a key and a rearwardly extending horizontally disposed arm that forms one element of a reverse toggle, a horizontally disposed link pivoted to the rearwardly extending arm of said key lever and forming the other element of said reverse toggle, an upright sub-lever of the first order pivoted above the link and connected at its lower end thereto, and an upwardly and rearwardly swinging type bar operatively connected to said sub-lever.

8. In a front-strike typewriting machine, the combination of a key lever of the first order having a rearwardly extending horizontally disposed arm that forms one element of a reverse toggle, a horizontally disposed link pivoted to the rearwardly extending arm of said key lever and forming the other element of said reverse toggle, an upright sub-lever of the first order pivoted above the link and connected at its lower end thereto, an upwardly and rearwardly swinging type bar, and a connecting link that extends forwardly from said sub-lever to said type bar, whereby a gradual acceleration of the type bar is effected as it approaches the printing position.

9. In a typewriting machine, the combination of a series of horizontally disposed key levers of the first order pivoted at different points fore and aft of the machine, a series of links connected to said key levers and extending longitudinally thereof, a series of sub-levers connected to said links, and a series of type bars operatively connected to said sub-levers.

10. In a front-strike typewriting machine, the combination of a series of horizontally disposed key levers of the first order pivoted at different points fore and aft of the machine, a series of links connected to said key levers, a series of upright sub-levers connected to said links, and a series of upwardly and rearwardly striking type bars operatively connected to said sub-levers.

11. In a typewriting machine, the combination of a series of horizontally disposed key levers of the first order pivoted at different points fore and aft of the machine; a

series of links connected to said key levers and arranged longitudinally of the key lever arms to which they are connected, said links and the arms of the key levers to which they are connected forming reverse toggles; a series of sub-levers connected to said links; and a series of type bars operatively connected to said sub-levers.

12. In a front-strike typewriting machine, the combination of a series of horizontally disposed key levers of the first order pivoted at different points fore and aft of the machine; a series of links connected to said key levers and arranged longitudinally of the key lever arms to which they are connected, said links and the arms of the key levers to which they are connected forming reverse toggles; a series of upright sub-levers connected to said links; and a series of upwardly and rearwardly striking type bars operatively connected to said sub-levers.

13. In a typewriting machine, the combination of a series of key levers, a series of toggle links connected to said key levers, a series of sub-levers connected to said toggle links and pivoted at progressively higher elevations as the sides of the system of sub-levers are approached, and a series of type bars operatively connected to said sub-levers.

14. In a typewriting machine, the combination of a series of key levers of the first order pivoted at different points fore and aft of the machine, a series of toggle links connected to said key levers, a series of sub-levers connected to said toggle links, the pivots of said sub-levers being arranged in an arc, and a series of type bars operatively connected to said sub-levers.

15. In a front-strike typewriting machine, the combination of a series of key levers, a series of toggle links connected to said key levers, a series of upright sub-levers connected to said toggle links and pivoted at progressively higher elevations as the sides of the system of sub-levers are approached, and a series of upwardly and rearwardly striking type bars operatively connected to said sub-levers.

16. In a typewriting machine, the combination of a series of key levers, a series of links connected to said key levers and arranged longitudinally of the key lever arms to which they are connected, said links and the arms of the key levers to which they are connected forming reverse toggles, a series of sub-levers connected to said links, the pivots of said sub-levers being arranged in an arc, and a series of type bars operatively connected to said sub-levers.

17. In a typewriting machine, the combination of a series of key levers of the first order pivoted at different points fore and aft of the machine, a series of links connected to said key levers and arranged longitudinally of the key lever arms to which they are

connected, said links and the arms of the key levers to which they are connected forming reverse toggles; a series of sub-levers connected to said links, the pivots of said sub-levers being arranged in an arc, and a series of type bars operatively connected to said sub-levers.

18. In a front-strike typewriting machine, the combination of a series of segmentally arranged upwardly and rearwardly striking type bars, a series of upright sub-levers pivoted in the rear of the type bars at progressively greater heights as the sides of the system are approached, the upper ends of said sub-levers being arranged in an arc that corresponds substantially to the arc in which the type bars are situated and being connected with said type bars, links connected to said sub-levers, and key levers connected with said links, each link and an arm of the associated key lever forming a toggle.

19. In a front-strike typewriting machine, the combination of a series of segmentally arranged upwardly and rearwardly striking type bars; a series of upright sub-levers of the first class pivoted in the rear of the type bars at progressively greater heights as the sides of the system are approached, the upper ends of said sub-levers being arranged in an arc that corresponds substantially to the arc in which the type bars are situated; links that extend forwardly from the upper ends of said sub-levers to the type bars; substantially horizontally disposed toggle links connected to said sub-levers at the lower ends thereof; and key levers having substantially horizontally disposed arms connected with said toggle links, each toggle link and an arm of the associated key lever forming a toggle.

20. In a typewriting machine, the combination of a series of type bars, a series of sub-levers of the first class, both sets of arms of the sub-levers extending greater distances from their pivots as the sides of the system of sub-levers are approached, one set of said arms terminating in a straight line across the machine, and key actuated toggles connected to said sub-levers.

21. In a front-strike typewriting machine, the combination of a series of segmentally arranged upwardly and rearwardly striking type bars, a series of upright sub-levers of the first class, both sets of arms of the sub-levers extending greater distances from their pivots as the sides of the system of sub-levers are approached, one set of said arms terminating in a straight line across the machine, and key actuated toggles connected to said sub-levers.

22. In a typewriting machine, the combination of a series of type bars, a series of sub-levers of the first class, both sets of arms of the sub-levers extending greater distances from their pivots as the sides of the system of sub-levers

of sub-levers are approached, means for connecting one set of arms of said sub-levers with the type bars, toggle links connected with the other set of arms of said sub-levers, and key levers of the first order connected with said toggle links and alined therewith.

23. In a typewriting machine, the combination of a series of type bars, a series of upright sub-levers of the first class, both sets of arms of the sub-levers extending greater distances from their pivots as the sides of the system of sub-levers are approached, means for connecting one set of arms of said sub-levers with the type bars, links connected with the other set of arms of said sub-levers, and key levers of the first order connected with said links, one arm of each key lever and the associated link connected thereto forming a reverse toggle that affords an accelerated movement of the type bar as it approaches the printing position.

24. In a front-strike typewriting machine, the combination of a series of upwardly and rearwardly striking type bars, a series of upright sub-levers of the first class, both sets of arms of the sub-levers extending greater distances from their pivots as the sides of the system of sub-levers are approached, means for connecting one set of arms of said sub-levers with the type bars, substantially horizontally disposed toggle links connected with the other set of arms of said sub-levers, and key levers of the first order having substantially horizontally disposed arms connected with said toggle links.

25. In a front-strike typewriting machine, the combination of a series of upwardly and rearwardly striking type bars; a series of upright sub-levers of the first class, both sets of arms of the sub-levers extending greater distances from their pivots as the sides of the system of sub-levers are approached; means for connecting one set of arms of said sub-levers with the type bars; substantially horizontally disposed links connected with the other set of arms of said sub-levers; and key levers of the first order, said key levers having rearwardly directed substantially horizontally disposed arms connected with said links, the rearwardly directed arm of each key lever and the associated link connected thereto forming a reverse toggle that affords an accelerated movement of the type bar as it approaches the printing position.

26. In a typewriting machine, the combination of a series of type bars; a series of sub-levers of the first class pivoted in an arc and connected with said type bars, both set of arms of said sub-levers extending farther from their pivots as the sides of the system of sub-levers are approached; links connected to said sub-levers; and key levers connected to said links.

27. In a typewriting machine, the com-

- bination of a series of type bars, a series of sub-levers of the first class connected therewith, a series of toggles connected with said sub-levers, and a series of keys for breaking said toggles; the carriers for said keys being pivoted at different points fore and aft of the machine.
28. In a typewriting machine, the combination of a series of type bars; a series of sub-levers of the first class connected therewith, both sets of arms of said sub-levers increasing in length from the center to the sides of the system of said sub-levers; a series of toggles connected with said sub-levers; and a series of keys for breaking said toggles, the carriers for said keys being pivoted at different points fore and aft of the machine to provide a substantially uniform leverage throughout the system.
29. In a front-strike typewriting machine, the combination of a series of segmentally arranged upwardly and rearwardly striking type bars; a series of upright sub-levers of the first class pivoted in an arc and having their upper ends connected with said type bars, both sets of arms of said sub-levers extending farther from their pivots as the sides of the system of sub-levers are approached; substantially horizontally disposed links connected to said sub-levers at the lower ends thereof; and key levers of the first order having rearwardly extending substantially horizontally disposed arms connected to said links.
30. In a typewriting machine, the combination of a series of type bars; a series of sub-levers of the first class connected therewith, both sets of arms of said sub-levers extending greater distances from their pivots as the sides of the system of sub-levers are approached; toggle links connected to said sub-levers; and key levers connected to said toggle links, said key levers being pivoted at different points fore and aft of the machine.
31. In a front-strike typewriting machine, the combination of a series of segmentally arranged upwardly and rearwardly striking type bars; a series of upright sub-levers of the first class connected therewith and adapted to vibrate fore and aft of the machine, both sets of arms of said sub-levers extending greater distances from their pivots as the sides of the system of sub-levers are approached; substantially horizontally disposed links connected to said sub-levers; and key levers pivoted at different points fore and aft of the machine and having substantially horizontally disposed arms which are connected to said links and forming with said links reverse toggles that effect a gradual acceleration of the type bars as they approach the printing position.
32. In a front-strike typewriting machine, the combination of a series of upwardly and rearwardly striking type bars arranged in an arc; a series of substantially horizontally disposed key actuated toggles greater in width than the series of type bars; and a series of upright sub-levers between said toggles and type bars, the sub-levers at the sides of the system being inclined to compensate for the difference in width between the system of toggles and the system of type bars.
33. In a front-strike typewriting machine, the combination of a series of upwardly and rearwardly striking type bars arranged in an arc; a series of substantially horizontally disposed key actuated toggles greater in width than the series of type bars; and a series of upright sub-levers in the rear of the type bars and interposed between said toggles and type bars and the upper ends of which are arranged in an arc substantially co-extensive with the arc in which the type bars are arranged, the sub-levers at the sides of the system being inclined to compensate for the difference in width between the system of toggles and the system of type bars.
34. In a typewriting machine, the combination of a system of key levers; a support or frame on which all of the system of said key levers are mounted, said support or frame being so connected to the frame of the machine as to be detachable therefrom without first dismounting any of the other parts of the machine; and a series of disconnectible devices which detachably connect the key levers to the other parts of the type actions.
35. In a typewriting machine, the combination of a system of type bars, and means for actuating said type bars including a system of key actuated toggles and also including detachable means connecting the toggles with the type bars, said system of toggles being detachable from the machine as a unit.
36. In a typewriting machine, the combination of a system of toggles, each comprising a key lever and a link; and type bars operatively connected to said links, each link having means for effecting a disconnection between the links and type bars to permit the removal of the system of toggles from the machine as a unit.
37. In a typewriting machine, the combination of a series of type bars, a series of substantially horizontally disposed key levers of the first class, a series of substantially horizontally disposed links connected to said key levers at the rear ends thereof and forming with said key levers toggles by which the type bars are actuated, each link having means for disconnecting said links from operative connection with the

type bars to permit the removal of said key levers and links as a unit from the machine.

38. In a typewriting machine, the combination of a series of key levers pivoted at 5 different points fore and aft of the machine and terminating at their rear ends in a single transverse plane; and a universal bar, the contact face of which bears the same relation to all of said key levers and is in a 10 single transverse plane.

39. In a typewriting machine, the combination of a support detachably secured to the framing of the machine, a series of depending individual hangers each detachably 15 secured to said support and situated at different points fore and aft of the machine, and a series of key levers pivoted to and supported by said hangers, each key lever being pivoted on an individual hanger.

20 40. In a typewriting machine, a series of hangers carrying pivoted devices and having each a longitudinally formed threaded hole eccentric of the center of the hanger whereby said hanger may be reversed to 25 change the position of the pivot of the pivoted device, and a fastening screw for each of said hangers.

41. In a typewriting machine, the combination of a base plate having two rows of 30 alternating holes, a single row of hangers each having a threaded hole arranged eccentric of the center of said hanger, a series of levers pivoted in said hangers, and two rows of securing screws, the hangers being 35 reversible so that the threaded holes therein may be arranged alternately above and below the pivots of the devices mounted in said hangers and may receive the two rows of securing screws.

40 42. In a typewriting machine, the combination of a series of type bars, a type bar segment in which said type bars are supported, parallel links on which said segment is mounted, key actuated means for shifting

said segment, a series of sub-levers, links 45 connecting said type bars and sub-levers and which afford a shifting of the segment without affecting the other type bar connections, and a series of key actuated toggles for actuating said sub-levers. 50

43. In a typewriting machine, the combination of a series of type bars, a type bar segment on which said type bars are supported, parallel links connected to the upper portion of said segment, a frame having a 55 transverse member that constitutes a rock shaft with forwardly projecting arms which extend therefrom parallel with said parallel links and which are connected to said segment at the lower portion thereof, key actuated means for shifting said segment on said parallel links and frame, actuating links connected to said type bars, sub-levers connected to said actuating links, and key actuated toggles connected with said sub-levers. 60 65

44. In a typewriting machine, the combination of printing instrumentalities, a series of key levers pivoted intermediate their ends, terminating at their rear ends in substantially the same transverse plane, and 70 having keys on their forward ends arranged in a plurality of transverse rows, the pivots of the several key levers being in different transverse rows so as to afford a uniform motion to the rear ends of the levers for a 75 uniform motion of said keys, means connected with said key levers at their rear ends for operating said printing instrumentalities, and a universal bar lying across the rear ends of said key levers. 80

Signed at Syracuse, in the county of Onondaga, and State of New York, this 12 day of July A. D. 1906.
